GLASS TUBE BAKING APPARATUS

Roland M. Gardner, Swampscott, Mass., assignor
to Sylvania Electric Products Inc., a corpora-
tion of Massachusetts

Application May 28, 1941, Serial No. 395,555

5 Claims. (Cl. 263—6)

This invention relates to heating ovens and more particularly to an oven for baking the coating of luminescent material applied to the walls of an elongated glass tube.

An object of this invention is to provide a heating oven in which elongated tubular glass envelopes may be baked.

Another object is to provide such an oven with means by which the tubular glass envelopes may be caused to pass therethrough.

A further object is to provide a smooth rotating surface for conveying the tubing through the oven.

Another object is to provide a tubing conveyor means which will keep the tubing straight and properly annealed.

A further object is to provide a means for feeding said tubular glass envelopes into said oven and means for ejecting the same therefrom.

Further objects, advantages, and features will be apparent from the following specification taken in conjunction with the accompanying drawings in which:

Figure 1 is a projection of the tube baker shown partly in section.

Figure 2 is a composite side elevation of the oven taken along the lines A—A, B—B, C—C respectively of Figure 6.

Figure 3 is a side elevation in section taken along the line D—D of Figure 6 showing the heat expansion equalizer assembly.

Figure 4 is a projection of the tubing etching device and the conveyor on which the etched tubing is carried into the oven.

Figure 5 is an end view partly in section of the tubing conveyor assembly, taken along the line E—E in Figure 4.

Figure 6 is a plan view of the belt of rollers.

Figure 7 is an end view in section showing the roof and side wall construction and the assembly for conveying the tubing through the oven.

Figure 8 is a sectional view of the air manifold assembly.

Figure 9 is a section showing the structure of the roof of the oven.

This heating oven is an improvement over that described in the copending application Serial No. 316,022, filed January 27, 1940, and issued as Patent No. 2,267,727, dated December 30, 1941. In an oven of the type herein described, the bulbs or tubes are carried through an oven on a belt of rollers 1. Each roller 1 has a long rod 2 extending therethrough. The side walls of the oven consist of two long channel iron sections,

the upper wall 3 and the lower wall 22. These walls are sufficiently spaced to permit the extension therebetween of the rods 2. These rods are supported at each end by a series of small rollers 4 on the outer ends thereof. These rollers run along the track 21 which is supported from the lower side wall 22 of the oven. To insure rotation of the rollers 1, one end of the rods 2 which pass therethrough has the gears 40 attached thereto as well as rollers 4. These gears 40 run on a rack 36 which, like the roller track 21, is also supported from the lower side wall 22 of the oven. As was pointed out above, the main support of the rods 2 is through the rollers 4. There is just enough weight on the rack 36 through the gears 40 to provide for the rotation of the rollers 1, and still not enough weight to cause any binding.

The rods 2 are led through the oven by a pair 20 of endless chains 5, with attachments 64 as later described for leading and maintaining spacing of the rollers, one on each end of the rods. These chains are turned through a driven sprocket 6 on the driven shaft 7 by the drive chain 8 from the drive sprocket 9 and drive shaft 10 projecting from the speed reducer 11 which reduces the speed of the motor 12 through the belt 13 and the wheels 14 and 15.

The burners 16, projecting through the roof 30 of the oven from the burner headers 17, are mounted through the channel iron units 18 which form the roof of the oven. Magnesia heat insulating blocks 19 are inserted in the channels of the channel iron units 18 and are held therein 35 by a covering of stainless steel sheets 20. Thus it is apparent that with this type of roof construction, one or more rows of burners may readily be removed for cleaning or replacement service. The side walls 3 and 22 of the oven are constructed in the same manner as the roof, i. e., the channel iron units have a filling of insulating material therein and a covering of stainless steel. Stainless steel is used as a covering on the walls and the roof and also as the material 40 from which the rollers 1 are formed because of its high degree of heat reflectivity and immunity to scaling at relatively high temperatures.

The oven is supported from the channel iron 50 side walls 3 and 22 by the supporting frame 24 through the I-beams 37 as shown in Figure 2. The tubing is ejected onto the table 28 from the rollers by the ejector bars 25 as more clearly shown in Figure 2. The canopy 26 and the duct 27 serve as a means through which the gases 55 formed by the carbonization of the nitrocellulose

binder in the fluorescent coating may be drawn off through end spaces 15 parallel to channel units 18 in an arrangement similar to that in Figure 4 of Patent No. 2,267,727, issued December 30, 1941. This was a copending application Serial No. 316,022, filed January 27, 1940. Much of the excess heat given off by the oven may be drawn off by connecting the duct 27 to an evacuating means. The evacuation of these gases being given off by the baking of the tubing may be further aided by the use of an air duct or manifold of the type described below in conjunction with Figure 8. However similar means, such as those described in co-pending application Serial No. 346,617, filed July 20, 1940, and issued as Patent No. 2,289,354, dated July 14, 1942, or in Patent No. 2,267,727, referred to above, may also be used without departing from the spirit of this invention.

Figure 2 is a side view in section of a part of the machine, particular attention being paid to the internal structure of the rollers 1 and the manner in which the rods 2 therethrough are held. The rods 2 are held within the rollers 1 in a manner to minimize the possibilities of wide temperature ranges over the tubing contact area of the rollers 1. The upper left portion of Figure 2, taken in part along the lines A—A of Figure 6 show how this is accomplished. The rods 2 are supported at approximately the longitudinal center of the rollers 1 by collars 29, see upper left of Figure 2, mounted on rods 2 and located within and held to the rollers 1 by counter-sunk rivets 30. The four corners of the collar at its points of contact on the inner wall of the roller 1 are slightly rounded to provide sufficient contact surface to insure a positive support. The disk 70, see lower left of Figure 2, fitted in the ends of each roller 1, and on the ends of the rods 2 and are not closely fitted with respect to the roller 1 but rather are loosely fitted so as to provide for any thermal expansion thereof.

By using a collar 29 with its corners slightly rounded rather than a disk which would give a 360 degree contact area, the danger of the rods 2 becoming distorted and out of shape as a result of excessive heat conducted thereto through the supporting means is minimized. So also is the danger of "cold spots" on the rollers minimized for the contacts on the rollers by the rod supporting means is kept at a minimum and thus a minimum amount of heat is conducted off from the surface of the rollers. As is shown in Figure 1 and as is clearly illustrated by reason of the location of section A—A in Figure 2, the locations of the inner supporting collars 29 are staggered longitudinally of the rollers in a manner to prevent the contact point of the collar on the roller from ever being in the same position longitudinally on any two adjacent rollers. This staggering is such that the section of Figure 2, upper left, shows a collar 29 in alternate rollers only. This is further protection against strains being set up in the tubing being baked, for any slight temperature variations in the roller 1 will not be concentrated at one point on the tubing as it would be if the collars 29 were located in the same position longitudinally on all the rollers.

As was pointed out above in connection with Figure 1, this baking oven is capable of baking tubing of small diameters. When the tubing has been baked it is ejected from the oven by an ejector bar 25 as shown in Figure 2. There are a series of such ejector bars projecting from a wheel 31 keyed to the driven shaft 1. These bars 25

are held in position relative to the wheel 31 by a spring 32 in an elongated slot 34 in the wheel 31, and the pin 33 lying in a slot 34¹ in the bar 25. The spring 32 is normally expanded, projecting the bar 25 outwardly. As the wheel 31 turns, the several ejector bars 25 successively come in contact with one of the rollers 1 and are consequently pushed down into their respective elongated slots 34, causing the associated spring 32 to contract.

As is shown in Figure 2, the rollers 1 spread apart somewhat as they finish their job of carrying the tubing, move downward, and start the return to the front of the oven to renew the tube-carrying cycle. Since the distance between the ejector bars is always constant, the increased spacing between the rollers 1 permits the ejector bars to move into this space. When the ejector bar is freed from its contact with the roller, the spring 32, previously contracted, will expand and the bar will eject the tubing 35.

Figure 3 shows the heat-expansion equalizer employed to provide for the expansion of the lower side wall 22 of the oven so that expansion of the channel iron 22 will not cause the chain 5 to become excessively taut. The angle iron 38 is bolted to the channel iron 22. The gear 40¹ on which the chain 5 travels turns about the shaft 41. The bars 39 are supported by the bar support 42 and extend through the bar guide 43 about the shaft 41 and through openings provided therefor in the angle iron 38. Thus when the channel iron 22 expands, the expansion will be taken up by the springs 44 on the bars 39, the angle iron 38 merely sliding along the bars 39 and exerting a contracting pressure on the springs by pressing the springs up against the bar guide 43. Thus the desired tension may be kept on the chain 5 at all times and the expansion of the channel iron 22 will be absorbed by the contraction of the springs 44.

Figure 4 shows the combination etching device and mechanism for feeding the tubing into the baking oven. The top portion of this may be seen in Figure 1 but it appears more clearly in Figure 4. The table 45 is supported on the legs 46. The frosted glass window 47 set in the top of the table is located over a light source encased in the housing 48. Thus tubing or bulbs, about to be etched and baked may first be inspected for coating defects.

The tubing is properly centered with respect to the etching stamps 50 by the guide 51. The tubing is rolled down the inclined blocks 52 so that the tubing comes in contact with the etching stamps 50, and rolls down further to be picked up by the conveyor wheels 53. There are a series of conveyor wheels 53 paired off with a series of friction wheels 54. The friction wheels turn faster than the conveyor wheels so that the tubing is rotated as it is being carried by the conveyor wheels thus enabling the burners 55 to properly burn in the etching on the tubing before the tubing rolls out of the conveyor wheel and along the arms 71 into the oven.

The driven shaft 56 on which the conveyor and friction wheels turn is driven through the driven sprocket 57 and the chain 58 from the drive sprocket 59 on the drive shaft 60. This drive shaft 60 is connected to and synchronized with the main drive. Figure 5 shows how this drive is accomplished. It also shows, the manner in which the gas supply manifold 61 is connected to the burners 55 through the connecting lines 62, and the arms 71 along which the tubing rolls from the conveyor wheels into the oven.

Figure 6 is a plan view of the oven without the

roof. It shows more clearly the relative location of the rollers 4 and the gears 40. It also shows the location at which the various sections shown in Figures 2 and 3 were taken. The section A—A is the one taken to depict the manner in which the ejector bars 25 operate as shown in the upper left portion of Figure 2. The section B—B is the one taken to depict the structure shown in the lower left portion of Figure 2. The section C—C is the one taken to depict the manner in which the endless chain 5 and the gears 40 and rack 36 operate as shown in the right hand portion of Figure 2. The section D—D is the one taken to depict the manner in which the heat expansion equalizer operates as shown in Figure 3.

Figure 7 shows how the rollers 1, the rods 2, and their associated assembly is constructed to provide for expansion due to heat generated during the operation of the oven. The roller 4 on the rod 2 runs along the track 21 provided therefor. This track is supported from the lower side wall 22 of the oven by the supporting arm 63. The endless chain 5 which carries the rollers 1 through the oven has an attachment 64 projecting up from the links of the chain. This attachment has a hole in the face thereof sufficiently large for the rod 2 to pass therethrough. There is one of these attachments for each rod and roller. In this manner the chain 5 carries the rollers 1 through the oven. The gears 40 on the rack 36 provide the means through which the rollers are rotated as they pass through the oven. This rack is supported from the lower side wall 22 of the oven by the supporting arm 64.

It should be noted in this figure, Figure 7, how the rollers 4, the gears 40 and their respective tracks are located in relationship to each other with respect to providing for thermal expansion. It is the outer end of the roller 4 which normally rides on the track 21. When expansion of the rod 2 takes place, the roller 4 may move out slightly with respect to the track 21. When this takes place, the roller will still ride on the track 21 for then its middle or its inner end will be in contact with the track. The same provision has been made with respect to the gear 40 and the rack 36. The gear 40 normally rides on the inner side of the rack 36. When expansion takes place it may move to the middle or the outer side of the bar and still function efficiently and properly.

Figure 7 also shows how further insulation may be obtained by providing two or more layers of channel irons filled with insulating material to form the roof of the oven through which the burners extend.

Figure 8 shows how an air manifold may be employed to aid in the evacuation of the gases given off during the baking process. The air manifold 65 is supported from the upper side wall 3 of the oven by the arm 66. The several connecting air lines 67 extend downward from the manifold 65 and terminate at a point slightly above the rollers 1. At a point near the bottom of these several air lines 67 there is a small vent 68. This vent is located in a position where the air blowing therefrom will blow into one of the ends of the tubing 69. Thus this air manifold

apparatus serves a very definite aid to proper and complete evacuation of the gases through the duct 27 as shown in Figure 1.

It should be noted that the air manifold shown in Figures 7 and 8 is adjustable as to height and as a result the efficiency of the manifold assembly is increased. Maximum efficiency is obtained when the stream of air emanating from the ports 68 is directed into the center of the tubing being baked. The manifold 65 is supported by the curved inner end of arm 66. This arm extends through a horizontally extending, vertically elongated opening 71 in side wall 3 and is locked in adjusted position by nut 73 threaded on arm 66 and bearing on plate 72 which straddles opening 71 to bear on side wall 3. Tightening of nut 73 draws the curved inner end of arm 66 against the manifold 65 to press it against the side wall 3. When it is desired to vertically adjust the manifold, nut 73 is loosened, and arm 66 moved vertically in opening 71.

Figure 9 shows in detail just how the channel iron units are assembled to form the roof of the oven. The channel of the channel iron 18 is filled with the insulating material 19 and the stainless steel sheets 20 which are wrapped around the channel iron serve to keep this insulating material in place and to reflect the heat from the burners down onto the tubing being baked. By using separate sheets of stainless steel for each channel iron, each channel iron assembly forms a separate, independent unit.

What I claim is:

1. An oven for baking glass tubing having: a series of spaced rollers; means for rotating said rollers; means for moving said rotating rollers through said oven; a series of ejector bars at the exit of said oven; and spring actuated means for causing said ejector bars to project themselves into the space between said rollers.

2. An oven for baking glass tubing, said oven comprising: a series of spaced rollers; means for rotating said rollers; means for moving said rotating rollers through said oven; apparatus for feeding said tubing onto said rollers; and spring-actuated means for ejecting the tubing from said rollers at the exit of said oven.

3. The oven of claim 2 and a manifold inside the oven for directing air into one end of the tube being baked.

4. An oven for baking tubes of glass or the like comprising: a series of spaced refractory rollers on which said tubes may be placed; mechanism for rotating said rollers; a frame of channel irons above and spaced from said rollers, said channel irons being placed with the open ends of the channels facing the rollers; a series of stainless steel channels covering the open ends of the iron channels; and a series of burners between the steel channels and the rollers to direct heat downwardly towards the rollers.

5. The oven of claim 2 and a manifold inside the oven for directing air into one end of the tubing being baked, the manifold being adjustable to direct the stream of air into the center of the end of said tubing.

ROLAND M. GARDNER.
